CLAIM

The ornamental design for a floor lamp, as shown and described.

DESCRIPTION

FIG. 1 is a perspective view of the floor lamp showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion indicated with numeric 9 in FIG. 2;

FIG. 10 is a perspective view of the floor lamp in an alternate condition of use, showing the lamp stem and hinges in a rotated configuration; and,

FIG. 11 is a perspective view of the floor lamp when it is folded.

The broken lines shown in the drawings represent portions of the floor lamp that form no part of the claimed design.
